(57) **CLAIM**

We claim the ornamental design for a terminal block of a battery pack, as shown and described.

DESCRIPTION

FIG. 1 is a front perspective view of a terminal block of a battery pack, showing our new design.

FIG. 2 is a rear perspective view of the terminal block of the battery pack shown in FIG. 1.

FIG. 3 is another rear perspective view of the terminal block of the battery pack shown in FIG. 1.

FIG. 4 is a rear view of the terminal block of the battery pack shown in FIG. 1.

FIG. 5 is a top view of the terminal block of the battery pack shown in FIG. 1.

FIG. 6 is a cross-section view of a first side of a terminal block of a battery pack, taken along line 6-6 shown in FIG. 5, the cross-section view of the second side being a mirror image thereof; and,

FIG. 7 is a plan view of FIG. 6.

The broken lines represent unclaimed subject matter and form no part of the claimed design. The dash-dot broken lines represent boundary lines. The dash-dot broken lines themselves form no part of the claimed design.
